CLAIM

The ornamental design for an instrument for use with a surgical robotic system, as shown and described.

DESCRIPTION

FIG. 1 shows a perspective view of an instrument for use with a surgical robotic system showing our new design; FIG. 2 shows a front view thereof;

FIG. 3 shows a rear view thereof;

FIG. 4 shows a side view thereof;

FIG. 5 shows another side view thereof;

FIG. 6 shows a top view thereof; and,

FIG. 7 shows a bottom view thereof.

In the above drawings the broken lines and the areas within the broken lines form no part of the claimed design.

1 Claim, 7 Drawing Sheets
